CREEL APPARATUS, INCLUDING GUARD SUPPORT FOR A CONE

Filed May 21, 1949

UNITED STATES PATENT OFFICE

2,545,203

CREEL APPARATUS, INCLUDING GUARD SUPPORT FOR A CONE

Walter E. Head, Miami, Okla., assignor to The B. F. Goodrich Company, New York, N. Y., a corporation of New York

Application May 21, 1949, Serial No. 94,604

6 Claims. (Cl. 242—130)

1

The invention relates to creel apparatus including guard supports for cones, cops, spools, and packages of cord, thread, yarn and other filamentary material.

In creel apparatus as it has been utilized heretofore in producing cord fabric for the manufacture of pneumatic tires for vehicles, cones of cord have been supported non-rotatably on the apparatus by cone-supporting spindles generally having an upwardly inclined disposition to facilitate the drawing-off or delivery of the cord axially over the upper or apex end of each cone.

It has been found desirable to vary the angle of upward inclination of the cone dependent upon whether the cord is random or precision wound on the cone-tube and, in addition, according to the characteristics and/or kind of filamentary material such, for example, as cotton, rayon, or nylon forming the cord, in order to minimize objectionable dropping or working of the cord over the peripheral edge of the base of the cone, especially when the cord is not being delivered, and to minimize cord breakage due to the same. This involves considerable loss of time in adjusting the spindles of the creel apparatus, when changes are made in the type of cone utilized or when more than one kind of cord is employed.

Objectionable breakage of the cord sometimes occurs for example, as the cord is delivered since; the cone is progressively reduced in diameter and the cord uncoils progressively faster and is thrown outwardly by centrifugal force, causing "ballooning" of the cord. Under abrupt reductions in the rate of delivery or the stoppage of delivery, the ballooning loosens the cord, especially at the peripheral edge of the base of the cone, whereby the cord drops over such edge and sometimes winds around the spindle.

This often results in cord breakage which involves considerable loss of time in joining the broken ends and conducting the cord through the respective parts of the creel apparatus. Defective cord fabric is produced, if the breakage is excessive or is not discovered promptly by the operator.

An object of the invention is to overcome the foregoing difficulties of the prior creel apparatus.

Other objects of the invention are to provide an improved creel apparatus including guard supports therefor; to provide for minimizing breakage of filamentary material utilized in the apparatus; to provide for supporting filamentary material at the peripheral edge of the base of a cone; to provide for preventing working or dropping of the filamentary material over such edge

2

of the cone; to provide for flexibly supporting the strands at the peripheral edge; to provide for accommodating an eccentric disposition of the cone on a cone-supporting spindle while supporting the strands at the peripheral edge; to provide for uniformity of angular disposition of the cones even though the cones have random or precision winding, and different cones contain different kinds of filamentary materials; and to provide for simplicity of construction, convenience of assembly and servicing, and for effectiveness and economy of operation.

These and other objects and advantages of the invention will be apparent from the following description.

In the accompanying drawings which form a part of this specification and in which like numerals are employed to designate like parts throughout the same,

Fig. 1 is a front elevational view of creel apparatus including guard supports therefor constructed in accordance with and embodying the invention, parts being broken away and in section; Fig. 2 is a plan view from above of a guard support.

Fig. 3 is a sectional view taken along line 3—3 of Fig. 2, and

Fig. 4 is a sectional view showing a modified construction of the guard support.

In the illustrative embodiment of the invention shown in the drawings, a plurality of cones, or cops, or spools, or other packages 10, 10 of filamentary material 11, 11 such, for example, as cord, thread, yarn or other filamentary material, wound upon cone-tubes 12, 12, are detachably and non-rotatably mounted upon cone-supporting spindles 13, 13 extending axially into the cone-tubes, which spindles have guard support elements or disks 14, 14 disposed thereon adjacent the bases 15, 15 of the cones. The spindles are suitably attached at 16, 16 to a vertical creel post 17 secured to a support surface or floor 18, and are adjustable to an upwardly inclined disposition so that the action of gravity on the cones 10, 10 facilitates holding the same on the spindles closely adjacent the guard support disks 14, 14 at the region of the peripheral edges 19, 19 of the bases of the cones. The guard disks 14, 14 make feasible effectively supporting the filamentary material 11, 11 to prevent its dropping or working over the edges 19, 19 and across the bases 15, 15.

In the construction shown in the drawings, each guard support disk 14 is of dished form, and may be of a suitable flexible material such, for example, as thermoplastic or thermosetting plas-

tic material, or molded rubber, natural or synthetic, or other rubber-like material which is flexible and desirably resilient in its cured condition. The guard disk 14 is concavo-convex and circular and may, if desired, have stiffening ribs 20, 20 and 21 extending radially and circumferentially, respectively, as shown especially in Figs. 2 and 3, which ribs may be formed in the molding of the disk.

The guard disk 14 may have a central mounting portion or cylindrical center-well portion 22 projecting axially outward or downward with the bottom wall 23 thereof having an aperture 24 through which the spindle 13 extends, the bottom wall 23 being backingly supported by a positioning washer 25 of stiff material such, for example, as steel, or alternatively of yieldable material such, for example, as resilient rubber attached to the spindle. When the rubber washer 25 is employed, it yields downwardly under pressure of the cone facilitating flexure of the sides of the center-well portion in a manner so as to enhance the pressure of the disk against the edge of the cone as the latter reduces in diameter with removal of the cord. The center-well portion 22 provides space for receiving the projecting end portion of the cone-tube 12, thereby facilitating axially centering the cone relative to the guard disk as well as the spindle 13 and the disposition of the concave surface 26 of the guard disk 14 in supporting relation to the filamentary material at the region of the peripheral edge 19 of the cone 10. Also, the center-well portion 22, as shown especially in Fig. 4, may have a plurality of internal side fins 31, 31 circumferentially spaced-apart and extending axially for engaging the cone-tube so as to further prevent the cord from dropping over the edge and winding on the spindle.

The concave surface 26 extends radially outward from and circumferentially about the center-well portion 22 for disposition at the peripheral edge 19 and desirably about the entire periphery of the cone to support flexibly the filamentary material against dropping over the edge 19, especially at the upper peripheral region of the base. The guard disk including its surface 26, when it is of resilient rubber-like material, is flexible and yieldable resiliently under pressure of the cone to facilitate close conformance about the base 15. Such yieldability is advantageous for continuity of support of the cord even though the cone be eccentric relative to the spindle 13, or has an irregular peripheral shape, or has an irregular surface configuration of the base. The flexure and resilient yieldability of the guard disk together with its dished shape makes feasible such conformance and support at the edge 19 when the cone is either fully or partially wound, as shown especially in Fig. 1, the resiliency permitting flexure of the disk against the edge 19 as the diameter of the cone decreases. Desirably, the upturned margin 27 of the guard disk projects beyond the peripheral edge 19 of the fully wound cone 10 to further facilitate peripherally supporting the filamentary material.

The supporting action at the periphery of the cone by the guard disk described hereinabove advantageously permits positioning the cone horizontally, or vertically, or at any desired angle therebetween. Also, it permits uniformity of the angle of inclination of all the spindles of the creel apparatus even though the cone by random wound or precision wound, and even though some

cones contain cotton cord while others contain rayon or nylon cord and the like.

When each cone 10 is positioned on the desired upwardly inclined spindle 13, the cone-tube 12 may be engaged and approximately centered by a finned cone-holder member 28 of wedge-shape fixedly secured to the spindle adjacent the guard disk 14 and the positioning washer 25, so that the cone-tube desirably terminates short of the bottom wall 23 of the center-well portion 22. This permits wedging the cone on the holder to prevent jerking the cone off the spindle while causing the cone to exert pressure upon the guard disk as the filamentary material 11 is unwound and delivered to an eyelet 29 carried by a vertical support post 30 spaced-apart from the creel post 17. The eyelet 29 may be suitably located on the support post 30 to promote drawing-off the filamentary material 11 over the upper or apex end of the cone 10 as shown in the drawings.

In the operation of the creel apparatus, each fully wound cone 10 is slipped base first over the free end of the desired spindle 13 and firmly wedged on the cone-holder member 28 so that the cone-tube 12 is within the center-well portion 22 and the base 15 at its peripheral edge 19 presses against the concave surface 26, the guard disk flexing resiliently to conform to and support the filamentary material 11 about the periphery of the cone. The guard disk peripherally and continuously supports the strands of filamentary material 11, thereby preventing entanglement with the spindle and the working of the filamentary material 11 over the peripheral edge 19. Thus, breakage of the filamentary material 11 from these sources of trouble is prevented effectively, which advantageously facilitates an improved quality of finished product at a relatively lower cost as compared to prior creel apparatus construction.

Variations may be made without departing from the scope of the invention as it is defined in the following claims.

I claim:

1. A guard member for a package of wound filamentary material, said guard member comprising a central mounting portion and comprising also a peripheral package-engaging portion of resilient rubber-like material of a thickness such that under pressure of the package said peripheral portion is self-sustaining by virtue of its stiffness without underlying support but is capable of slight resilient flexure under such pressure of the package, said peripheral portion being dished for engagement of said package by the resilient pressure of said peripheral portion around the peripheral edge of the base of the package and continuance of such resilient engagement progressively across said peripheral portion as the package is reduced in size by removal of the filamentary material, to support yieldably the filamentary material against working over said peripheral edge of the package.

2. A guard member for a package of wound filamentary material, said guard member comprising a full molded disk of rubber-like material having a central mounting portion and having also a peripheral package-engaging portion of resilient rubber-like material of a single wall thickness sufficient to be self-supporting under pressure of the package by virtue of the stiffness of said peripheral portion without underlying support but capable of slight resilient flexure under such pressure of the package, said peripheral portion being dished in its unstressed condition

for engagement of said package by the resilient pressure of said peripheral portion around the peripheral edge of the base of the package and continuance of such resilient engagement progressively across said peripheral portion as the package is reduced in size by removal of the filamentary material, to support yieldably the filamentary material against working over said peripheral edge of the package.

3. A guard member for a package of wound filamentary material, said guard member comprising a full moldeed unitary disk of flexible rubber-like material having a center-well mounting portion projecting axially outward of said disk for receiving a projecting end of the package at its base and said disk having also a peripheral package-engaging portion extending laterally outward from said center-well portion, said peripheral portion being of resilient rubber-like material of a single wall thickness sufficient to be self-supporting under pressure of the package by virtue of the stiffness of said peripheral portion without underlying support but capable of slight resilient flexure under such pressure of the package, and said peripheral portion being dished in its unstressed condition for engagement of said package by the resilient pressure of said peripheral portion around the peripheral edge of the base of the package and continuance of such resilient engagement progressively across said peripheral portion as the package is reduced in size by removal of the filamentary material, to support yieldably the filamentary material against working over said peripheral edge of the package.

4. A guard member for a package of wound filamentary material, said guard member comprising a full molded unitary disk of circular form and of flexible rubber-like material, said disk having a center-well mounting portion of cylindrical form projecting axially outward of said disk for receiving a projecting end of the package and terminating in a closed end wall having a central spindle-receiving aperture therethrough, said disk having also a peripheral package-engaging portion extending radially outward from said center-well portion and being of resilient rubber-like material of a single wall thickness sufficient to be self-supporting under pressure of the package by virtue of the stiffness of said peripheral portion without underlying support but capable of slight resilient flexure under such pressure of the package, said peripheral portion being dished in its unstressed condition for engagement of said package by the resilient pressure of said peripheral portion around the peripheral edge of the base of the package and continuance of such resilient engagement progressively across said portion as the package is reduced in size by removal of the filamentary material, to support yieldably the filamentary material against working over said peripheral edge of the package.

5. Apparatus for mounting a package of wound filamentary material to permit delivery of said material therefrom, said apparatus comprising a package-mounting element, and a guard

member on said element, said guard member comprising a central mounting portion at said element and comprising also a peripheral package-engaging portion of resilient rubber-like material of a thickness such that under pressure of the package said peripheral portion is self-sustaining by virtue of its stiffness without underlying support but is capable of slight resilient flexure under such pressure of the package, said peripheral portion being dished in a direction along said package-mounting element for engagement of said package by the resilient pressure of said peripheral portion around the peripheral edge of the base of the package and continuance of such resilient engagement progressively across said peripheral portion as the package is reduced in size by removal of the filamentary material, to support yieldably the filamentary material against working over said peripheral edge of the package.

6. Apparatus for mounting a package of wound filamentary material to permit delivery of said material, said apparatus comprising a package-mounting spindle, and a guard member on said spindle, said guard member comprising a full molded unitary disk of flexible rubber-like material having a center-well mounting portion projecting axially outward of said disk at and along said spindle for receiving a projecting end of the package at its base and said disk having also a peripheral package-engaging portion extending laterally outward from said center-well portion, said peripheral portion being of resilient rubber-like material of a single wall thickness sufficient to be self-supporting under pressure of the package by virtue of the stiffness of said peripheral portion without underlying support but capable of slight resilient flexure under such pressure of the package, said peripheral portion being dished in its unstressed condition in a direction along said spindle for engagement of said package by the resilient pressure of said peripheral portion around the peripheral edge of the base of the package and continuance of such resilient engagement progressively across said peripheral portion as the package is reduced in size by removal of the filamentary material, to support yieldably the filamentary material against working over said peripheral edge of the package.
